UNITED STATES PATENT OFFICE

2,230,737

ELECTRIC SWITCH

John M. Wilde, Schenectady, N. Y., assignor to
 General Electric Company, a corporation of
 New York

Application November 13, 1939, Serial No. 303,971

5 Claims. (Cl. 200—166)

My invention relates to electric switches, more particularly to contact or tip means for electric switches, and has for its object a simple, reliable and inexpensive reversible contact which is arranged to compensate for wear both of itself and of its cooperating contact.

In the construction of electric switches, more particularly contactors in which the switch contacts or tips engage in abutting relation with each other, it is customary to provide for wipe between the contacts. This wipe is defined as the distance the movable contact or tip would move past the position of the stationary contact or tip contact surface if the stationary contact were not there.

The wipe is accomplished by mounting the movable tip resiliently on a support having a fixed distance of travel so related to the contact tip that the movable tip support is caused to yield resiliently by the engagement of the movable tip with the stationary tip. This wipe causes a rolling or sliding action of the movable tip on the stationary that is beneficial in maintaining clean contact surfaces and in avoiding welding and pitting.

Normal operation reduces the wipe by mechanical wear and electrical burning. This wear and consequent reduction of the wipe decreases the efficiency of the switch contacts. It is common practice to renew the switch contacts when the contacts have worn to such an extent as to decrease the wipe to one-half of its original value.

It will be understood that this wear is quite fast in certain contactors which open and close many times a minute, or even second, during their operation. The contacts are thus the limiting feature in the life of the device. In some applications, the contacts must be renewed on account of wear after a few months operation.

In carrying out my invention, I provide a switch member having a plurality of contacts or tips and mounted so that it may be easily loosened and moved to bring another contact into working position. This new contact is, furthermore, constructed to present not only a new unworn contact, but also to offset or compensate for the wear on the other cooperating contact which is not renewed. Thus, when the multiple contact member, which preferably is the stationary one, is reversed or reset, the original contact wiping conditions are reestablished.

For a more complete understanding of my invention, reference should be had to the accompanying drawing, the single figure of which is a fragmentary side elevation view partly in section

of an electromagnetically operated contactor embodying my invention.

Referring to the drawing, I have shown my invention in one form as applied to an electromagnetically operated contactor provided with a base 5 or support 10 which preferably is made of a suitable electrically insulating material such as slate or a moulded compound. Pivotaly mounted on this support 10 is an operating shaft having a square portion 11 to which an arm 12 carrying 10 the movable contact is secured. As shown, the arm 12 is clamped to the shaft by means of suitable bolts 13 and 14.

The movable contact 15 carried by the arm 12 is a strap of electrically conducting material, 15 preferably copper, having a rectangular aperture 16 through which extends a rectangular post 17 securing the contact to the arm 12, the post 17 carrying a helical spring 18 which presses the lower portion of the contact against the arm 12. 20 The upper end of the arm 12 is provided with a pivot ridge 19, against which the contact 15 rests when the contactor is in the open position shown, and with a second pivot projection 20 in position to be engaged by the lower end of the contact 15, as shown. The lower end of the contact 15 is electrically connected through an electrically conducting cable 21 to a terminal post 22 secured to the base 10. 25

Secured also to the base 10 is a support 23 in 30 the form of a strap and made of a suitable electrically conducting material. It is secured to the base by screws 24 and 25 and has a lower portion 26 extending outward from the base at substantially right angles thereto. A reversible stationary contact member 27 embodying my invention is mounted on this portion 26 and pivotally secured to the end of the portion 26 by a screw 28. This contact member 27 is substantially U-shaped, its shape, of course, depending upon the 35 position and shape of the movable contact 15. The outer faces 29 and 30 of the two upright laterally extending side portions of the member selectively form contact surfaces. As shown, the surface 29 is in position to be engaged by the 40 contacting surface 31 of the contact 15 when the shaft 11 is rotated in a clockwise direction. 45

Moreover, the screw 28 engages the base portion of reversible contact at the point 32 which is considerably nearer the contact surface 29 than 50 to the surface 30. Thus, when the screw is loosened and the contact turned about the screw as a pivot to bring the surface 30 into contacting position, the surface 30 will be in the dotted position 30a which is farther away from the pivot 32 55

than the surface 29 in its contacting position. The distance between these two surfaces 29 and 30a is sufficient to offset or compensate for the wear on the contact surfaces 29 and 31. It is contemplated that the contact 27 will be reversed when the contacting surfaces 29 and 31 have worn sufficiently to take up about one-half of the wipe originally provided. Therefore, the distance between the surface 29 and surface 30a is made 10 equal to one-half the wipe.

It will be understood that when the shaft 11 is turned by suitable means, such as an electromagnet, not shown, to close the switch, it is turned considerably farther than the amount required 15 to actually bring the contacts into engagement whereby the wipe is produced. After the two contacts engage, the spring 18 is compressed by the continued movement of the arm 12.

To assure the proper positioning of the reversible contact 27, apertures 33 and 34 are provided 20 in its base on opposite sides of the screw 28 and spaced equidistances from the screw. A cooperating dowel pin 35 is secured to the support 26 in position to enter one of these holes and thus 25 secure the contact in its correct angular position about the screw 28.

While I have shown a particular embodiment 30 of my invention, it will be understood, of course, that I do not wish to be limited thereto, since many modifications may be made and I, therefore, contemplate by the appended claims to cover any such modifications as fall within the true spirit and scope of my invention.

What I claim as new and desire to secure by 35 Letters Patent of the United States is:

1. A switch comprising a support, a contact member having a base portion and a plurality of contact portions, and means releasably securing said base portion to said support at a point nearer one contact portion than another contact portion.

2. A switch comprising a support, a contact member having a base portion and a plurality of contact portions extending laterally with respect to said base portion, and means for pivotally securing said base portion to said support at a point nearer one contact portion than another. 5

3. A switch comprising an electrically conducting support, a U-shaped contact member, and means for releasably securing the base of said contact member to said support at a point nearer 10 one side than the other whereby said contact member can be mounted with said one side in a switching position and thereafter reversed about said pivot to bring the other side into a switching position. 15

4. A switch comprising a movably mounted switch contact, a support, a stationary contact member provided with a base portion and a contact at each end of said base portion, and means pivotally securing said base portion to said support at a point nearer one of said contacts with 20 said one of said contacts in position to be engaged by said movable contact whereby said contact member can be reversed about said pivot to bring said other contact into position to be engaged by said movable contact. 25

5. A switch comprising a movably mounted switch contact, an electrically conducting support, a stationary contact member provided with a base portion and a contact at each end of said base portion extending laterally with said base portion, and means pivotally securing said base portion to said support at a point nearer one of 30 said contacts than the other with said one of said contacts in position to be engaged by said movable contact whereby said contact member can be reversed about said pivot to bring said other contact into position to be engaged by said movable contact, and means for positioning said 35 contact member on said support. 40

JOHN M. WILDE.
